UNCURLING GUIDE

Hans Hacklander, Linden, N. J., assignor to The
Singer Manufacturing Company, Elizabeth,
N. J., a corporation of New Jersey

Original application September 22, 1939, Serial
No. 296,031. Divided and this application
November 13, 1939, Serial No. 303,946

8 Claims. (Cl. 112—20)

This invention relates to fabric guides for sewing machines and more particularly to uncurling guides for hosiery seaming sewing machines.

The primary object of the present invention is the provision of an improved latching device for locking the uncurling guide in operative or retracted position.

Another object of this invention is to provide a latching device comprising two latches each having its own control-lever whereby the respective latches may be alternately shifted into inoperative positions.

With the above and other objects in view, as will hereinafter appear, the invention comprises the devices, combinations, and arrangements of parts hereinafter set forth and illustrated in the accompanying drawing of a preferred embodiment of the invention, from which the several features of the invention and the advantages attained thereby will be readily understood by those skilled in the art.

In the accompanying drawing, Fig. 1 is a front elevation of the upper portion of the machine-frame, showing the uncurling device in its operative position (full lines) and in its inoperative position (dotted lines).

Fig. 2 is a disassembled perspective view showing the various elements of the uncurling guide latching device and the means for releasing the same.

Fig. 3 is a front elevation of the uncurling guide latching device with the control-arms partially broken away to show the relative positions of the latches when the guide is in operative position.

Fig. 4 is a view similar to Fig. 3, showing the relative positions of the latches when the guide is in inoperative position.

In the embodiment of the invention selected for illustration my improved uncurling guide is shown as applied to a so-called "cup-feed" sewing machine having a standard 1 and an overhanging bracket 2 from which depends the uncurling guide. Supported by the standard 1 is a feed-cup 3 which cooperates with a second feed-cup (not shown) in advancing the fabric past the stitching mechanism. As shown in Fig. 1, the uncurling guide is located directly in front of the feed-cups and functions to uncurl and direct the edges of the fabric preparatory to stitching.

For a more detailed description of the cup-feed sewing machine, reference may be had to my copending application Serial No. 296,031, filed September 22, 1939, of which this application is a division.

The uncurling guide illustrated includes a central guiding plate 4 terminating at its upper end in a supporting head-portion 5. Disposed on opposite sides of the guiding plate adjacent its lower end are uncurlers 6 yieldingly pressed by the usual spring 7 against the faces of the guiding plate. The mounting for the uncurling guide is identical with that shown and described in my copending application Serial No. 303,947, filed November 13, 1939.

Referring to Fig. 2, it will be seen that the supporting head 5 of the central guiding plate 4 is formed with a bearing aperture 8 through which projects a cylindrical boss 9 formed upon a stationary locking disk 10. The locking disk is supported so that its boss 9 is rigidly fastened face to face to a vertical plate 11 by a bolt 12, with the head 5 of the central guiding plate 4 interposed between the vertical plate 11 and the locking disk 10. To permit the central guiding plate 4 to turn freely upon the boss 9, the width of said boss is slightly in excess of the thickness of the central guiding plate.

To positively hold the uncurling guide in set positions, the locking disk 10 is formed with two stop-notches 13 and 14. Cooperating with these stop-notches are two pivotal latches 15 and 16 biased toward each other by a coil-spring 17 connected by shouldered screws 18 and 19 to the free ends of the latches. The two latches are apertured as at 20 and 21 to receive a fulcrum-stud 22 threaded into an ear 23 formed on the head 5 of the central guiding plate 4. Latch 15 has secured to it by screws 18 and 24 a control-lever 25 having at its free end an offset finger-piece 26. Latch 16 has similarly secured to it by screws 19 and 27 a control-lever 28 having at its free end an offset finger-piece 29. The two control-levers 25 and 28 cross each other, the control-lever 28 being bent as at 30 to provide clearance for the control-lever 25, whereby independent movement of one control-lever will not interfere with the other control-lever.

Referring now to Fig. 1, it will be understood that the uncurling guide is shown in full lines in its normal operative position. In such position the latch 15 is disposed in the notch 13 in the locking disk 10, see Fig. 3, while the latch 16 rides on the periphery of the locking disk, the latch 15 being held in the notch 13 by the coil-spring 17. When it is desired to shift the uncurling guide out of operative position and into the position shown in dotted lines in Fig. 1, pressure is manually applied in an upward direction upon the finger-piece 26 of the control-lever

25, which lever in response to this pressure moves in a counterclockwise direction and the initial movement of the control-lever 25, which movement is independent of the central guiding plate 4, raises the latch 15 out of the notch 13. When the latch is entirely clear of the notch, the control-lever 25, the control-lever 28, and the central guiding plate 4 move as a unit, turning the guide about the axis of the cylindrical boss 9 on the locking disk 10 until the latch 16 registers with and enters the notch 14 in the locking disk. During this turning of the guide the latches 15 and 16 ride upon the periphery of the locking disk 10, the coil-spring 17 being sufficiently strong so that pressure on the control-lever 25 in a counterclockwise direction will not tend to lift the latch 15 off the periphery of the locking disk 10, but will effect a substantial rigid connection between the control-lever 25 and the guide.

When it is desired to return the uncurling guide to operative position, such as shown in full lines in Fig. 1, pressure is manually applied in a downward direction upon the finger-piece 29 of the control-lever 28, which lever in response to this pressure moves in a clockwise direction, thereby first moving the latch 16 out of the notch 14 and, secondly, turning the guide about the boss 9 until the latch 15 registers with and enters the notch 13 in the locking disk 10. The two control-levers 25 and 28 are designed for independent operation and when it is desired to move the guide into inoperative position control-lever 25 is operated, and when it is desired to return the guide to operative position control-lever 28 is operated.

From the above description, it will be apparent that an uncurling guide has been provided having means including two latches, each having its own control-lever for positively locking the guide in or out of operative position. In the embodiment chosen for illustration, the control levers 25 and 28 are each formed of sheet-metal and each is removably secured to its respective latch by means of screws. Obviously the control-levers may be formed integral with the latches without departing from the invention. In Fig. 1, it will be seen that the free ends of the control-levers, when the guide is in operative position, are preferably positioned in advance of the guide so that the operator may conveniently strike the control lever 25 with an upward movement of the hand to shift the guide into inoperative or loading position, and strike the control-lever 28 with a downward movement of the hand to shift the guide back into operative position.

It is obvious that changes in the details of construction and the arrangement of the parts may be made without departing from the spirit of the invention as set forth in the appended claims.

Having thus set forth the nature of the invention, what I claim herein is:

1. A fabric guide for sewing machines having an operative and an inoperative position, means for supporting said guide whereby it may be moved from one to the other of said positions, a latch for holding said guide in operative position, a control-lever for releasing said latch and moving the guide when operated in one direction, a second latch for holding said guide in inoperative position, and a second control-lever for releasing said second latch and moving the guide when operated in one direction.

2. A fabric guide for sewing machines having an operative and an inoperative position, means

for supporting said guide whereby it may be moved from one to the other of said positions, a stationary locking disk, a latch cooperating with said locking disk for holding said guide in operative position, a control-lever for releasing said latch and moving the guide when operated in one direction, a second latch cooperating with said locking disk for holding said guide in inoperative position, and a second control-lever for releasing said second latch and moving the guide when operated in one direction.

3. A fabric guide for sewing machines having an operative and an inoperative position, means for supporting said guide whereby it may be moved from one to the other of said positions, a latch for holding said guide in operative position, a control-lever secured to said latch for releasing the same and moving the guide when operated in one direction, a second latch for holding said guide in inoperative position, and a second control-lever secured to said second latch for releasing the same and moving the guide when operated in one direction.

4. A fabric guide for sewing machines having an operative and an inoperative position, means for supporting said guide whereby it may be moved from one to the other of said positions, a latch for holding said guide in operative position, a control-lever for releasing said latch and moving the guide when operated in one direction, a second latch for holding said guide in inoperative position, and a second control-lever for releasing said second latch and moving the guide when operated in one direction, said control-levers crossing each other with their free ends in proximity to each other for convenient manipulation by the operator.

5. A fabric guide for sewing machines having an operative and an inoperative position, means for supporting said guide whereby it may be moved from one to the other of said positions, a latch for holding said guide in operative position, a control-lever for releasing said latch and moving the guide when operated in one direction, a second latch for holding said guide in inoperative position, a second control-lever for releasing said second latch and moving the guide when operated in one direction, and a spring acting between said first and second latches for yieldingly maintaining the respective latch in its holding position.

6. A fabric guide for sewing machines having an operative and an inoperative position, means for supporting said guide whereby it may be moved from one to the other of said positions, a latch fulcrumed on and movable with said guide for holding it in operative position, a control-lever for releasing said latch and moving the guide into inoperative position when manually operated in one direction, a second latch fulcrumed on and movable with said guide for holding it in inoperative position, and a second control-lever for releasing said second latch and moving the guide into operative position when manually operated in the opposite direction, said control-levers having their extremities disposed so that an upward movement of the operator's hand can move the guide into inoperative position and a downward movement of the operator's hand can move the guide into operative position.

7. A fabric guide for sewing machines having an operative and an inoperative position, said fabric guide including a central guiding plate, means for supporting said guide whereby it may be moved from one to the other of said positions,

a latch fulcrumed on said central guiding plate and serving to lock said guide in operative position, a second latch fulcrumed on said central guiding plate and serving to lock said guide in inoperative position, and a pair of control-levers each one of which is secured to its respective latch, said control-levers crossing one another and disposed so that an upward movement of the operator's hand against one control-lever will release its latch and move the guide into inoperative position and a downward movement of the operator's hand against the other control-lever will release its latch and move the guide into operative position.

8. In a sewing machine uncurling guide having an operative and an inoperative position, a central guiding plate, means for supporting said central guiding plate whereby the guide may be moved from one to the other of said positions, a

stationary disk having a plurality of stop-notches formed therein, a latch fulcrumed upon said central guiding plate and cooperating with one of said stop-notches in said stationary disk to lock said guide in operative position, a second latch fulcrumed on said central guiding plate and cooperating with another of said stop-notches in said stationary disk to lock said guide in inoperative position, a pair of sheet-metal control-levers each one of which is secured to its respective latch, said control-levers disposed so that a manual shifting of one lever will release its latch and move the guide into inoperative position and a manual shifting of the other lever will release its latch and move the guide into operative position, and spring means for yieldingly maintaining the respective latch in its stop-notch.

HANS HACKLANDER.
